UNITED STATES PATENT OFFICE.

ROBERT LEE, OF CINCINNATI, OHIO.

IMPROVEMENT IN HORSESHOES.

Specification forming part of Letters Patent No. 159,191, dated January 26, 1875; application filed December 19, 1874.

To all whom it may concern:

Be it known that I, ROBERT LEE, of Cincinnati, Hamilton county, Ohio, have invented a new and useful Horseshoe, of which the following is a specification:

My invention relates to those horseshoes which have separable toe and heel pieces or calks; and consists in a rotatable pin which is headed or riveted into the shoe, and has a flattened depression on one side. It is placed in such a position, with regard to the socket for the reception of the shank of the calk, as to permit the lower end of the shank of the calk to be passed through the flattened depression. The shank of the calk is coved, so that the side of the pin opposite to the flattened depression may be turned therein, and thus secure the bolt in position.

In the accompanying drawing, Figure 1 is a perspective view of a horseshoe embodying my invention, the shoe being shown in the inverted position, two of the calks being removed. Fig. 2 is a partially-sectioned plan of the under side of the shoe, two of the calks being locked in and one unlocked for withdrawal. Figs. 3 and 4 are enlarged vertical sections through the shank and socket of one of the calks in the locked and unlocked conditions respectively.

The body A of my horseshoe may be cast malleable iron, or may be forged wrought-iron, or cast-steel. B are sockets to receive the shanks C of calks D. Said shanks have coves or concave notches e. Horizontal perforations F receive pins F, which are securely riveted in their places, and are provided with nicked heads G, to enable them to be turned. Each pin has a depression, f, which, being brought toward the socket, leaves a free opening for the insertion or removal of the calk. After insertion in their respective sockets, the calks are secured by turning the pins F around, un-

til their round portions engage in the notches e, and thus securely lock or retain the calks to their places.

The nicked heads of the pins C are entirely buried or countersunk in the body, so as to leave no projection which might otherwise be liable to strike against rocks or other impediments, and thus loosen the calks. The calks bear firmly by their square shoulders K on the sole of the shoe.

After turning the pin around with its flat surface toward the shank-socket, the calk can be easily detached by prying underneath its shoulder by means of the same screw-driver by which the pin has been turned.

This shoe is of great convenience and utility for replacing worn toes and heels with new ones, or smooth calks with rough or sharpened ones in frosty weather, and all this without removing the shoe from the horse's foot.

It will be seen that the calks have no direct bearing upon the hoof, and press only through the medium of the body A, with an equal and easy bearing all around.

The bearing-shoulders of the calk may be either all around, as shown for the heel-pieces, or only on two opposite sides, as shown for the toe-piece.

I claim as new and of my invention—

The sunken and riveted rotatable pins F, having nicked heads G and flattened depressions f, in combination with a horseshoe, A, having sockets B, and calks D, having coved shanks C e, as and for the purpose set forth.

In testimony of which invention I hereunto set my hand.

ROBERT LEE.
